DEVICE FOR CARRYING CHILDREN

William Arthur Hancock and Brenda Anderson
 Hancock, Maroubra, near Sydney, New South
 Wales, Australia

Application November 20, 1944, Serial No. 564,370
 In Australia October 29, 1943

8 Claims. (Cl. 224—6)

1

This invention relates to means for carrying small children say between the ages of six months to two years

With the prevailing difficulties due to curtailment of transport, also the necessity for people particularly women to go out for essential food purchases and the like which hitherto were delivered, it has been a tiresome operation for women with young children to cope with the carrying of parcels while holding a baby and the present invention has been specially devised to meet the urgent need of effectively carrying a child in a comfortable and natural sitting position without imposing undue strain on the person and whereby safe control of such child is had while leaving the arms free. By the use of the present invention the weight of the child is distributed about those body parts best suited for the purpose and the limbs are not cramped or restricted in a way to cause discomfort. The device is easily and cheaply manufactured and can be folded away into small compass when not required for use.

According to this invention the device for carrying a child consists of a supporting sling of flexible form adapted to take diagonally across the body of a wearer from over one shoulder to the opposite side, and preferably having length adjustment; the sling is affixed at its ends to two flaps connected each to an end of a seat base of flexible material having provision to retain its shape and being padded and having an edge formation adapted to bear against the said body at or below the top of hip bone in a comfortable manner. The flaps are provided with a back supporting member adapted to extend around the body of a child to support it in a natural sitting position, and one of the flaps is twisted between the seat base and back supporting member so as to provide a direct supporting line from the outermost edge of the sling contacting the shoulder of the wearer to the remote edge of the seat base. The result of this arrangement is to hold the child, in the front of the wearer to one side with the child's legs positioned at the front of said wearer and enabling the wearer's arm at that side to be crooked or curved around said child when required but allowing free movement to both arms.

In order to describe the invention more fully reference will now be made to the drawing accompanying and forming part of this complete specification and wherein:

Figure 1 is a perspective of the device for carrying a child taken from the inside, while

2

Figure 2 is another perspective of the device taken from the outside.

Figure 3 is a perspective showing the device in use and indicating the freedom allowed the arm on that side.

Figure 4 is another perspective of the lower portion of the seat, while

Figure 5 is a cross section of the seat proper.

The device for carrying a child consists of a 10 sling 6 of suitable cloth material appropriately strengthened where required and of a width to take across an appreciable area of the shoulder to distribute the "pull" and it has slide buckle and fastenings 7 or the like connecting it in an 15 adjustable manner with an anchoring strap 8 affixed to the top edge of a body flap 9 later referred to.

The other end of sling 6 connects to a second 20 and angular shaped body flap 10 which is twisted through a half turn and preferably quilted and joins a seat base 11, and a back support 12 connects across the top of both flaps 9 and 10.

The seat base 11 of hollow form as shown in 25 Figures 4 and 5 is contoured at the corner as indicated at the edge 13 approximately complementary to the body of a wearer say at one side of the front below the hip bone and contains a shaped seat retaining plate 14 say of plywood or other suitable material with its edge contoured 30 at 15 to conform to the shaping of the seat base 11 and adapted to retain such base in shape while padding or a removable cushion 16 is positioned over such plate 14 and there is a rear flap 17 through which the parts may be removed 35 and replaced and it is closed by press studs or any other suitable means.

In some cases the flap 17 may tuck in and have no fastening devices.

A pocket (not shown) may be provided under 40 the seat base 11 or at the side or other point to carry a napkin or other article.

In use to fit the device the sling 6 is fitted over the right shoulder with the head and left arm inserted through said sling 6 which continues 45 down the back well under the left shoulder blade with the twisted flap 10 around the left hip from the back. The sling 6 is adjusted by the buckles and fastener 7 until the seat base 11 lies flat just below the top of hip bone in a comfortable manner. The child is placed well back and square on the seat base 11 close in to the wearer's body with the back support 12 taking firmly around the child's back and the legs are to the front. The twist in the flap 10 provides 55 a direct supporting line from the outermost edge

of the sling 6 contacting the shoulder of the wearer to the remote edge (that is the rear edge) of the seat base. This arrangement assures that when the supporting pull is exerted the back support 12 is drawn in affording a safe holding pressure about the child which is drawn into the wearer's body.

If the child is asleep or is a baby the device may be adjusted to tilt the seat and allow the baby's head to rest on crook of the left arm.

As the child sits on a cushion supported by a solid base rendered possible by the plate 14 there is no possibility of chafing or any restriction of the circulation or any of the other discomforts usually incurred when being carried around in the arms or merely supported by an ordinary flexible sling device.

In bad weather a shawl or the like can be wrapped around the seat portion or the device worn under a loose top coat.

The seat base interior can be removed for airing and the cloth portion of the device can be washed or boiled.

Although the device has been described as applied to one side it may be made in both left and right hand types to suit different requirements.

We claim:

1. An improved device for carrying a child, comprising a seat base, sling means providing legs of substantial width connecting the ends of the seat base and adapted to extend diagonally across the body of a wearer from over one shoulder to the opposite side of the body, and a back supporting member connected across the legs of said sling means, the leg normally extending across the back of the wearer being twisted through a half turn adjacent its point of juncture with said seat base to provide a direct supporting line from the outermost edge of the sling means contacting the shoulder of the wearer to the remote edge of the seat base.

2. An improved device for carrying a child, comprising a seat base, sling means consisting of a flap connected to each end of said seat base and a sling of flexible material connected to each flap and adapted to extend diagonally across the body of a wearer from over one shoulder to the opposite side of the body, and a back supporting member connected at each end to one of said flaps and spaced from said seat base, one of said flaps being twisted through a half turn between said seat base and back supporting member to provide a direct supporting line from the outermost edge of the sling contacting the shoulder of the wearer to the remote edge of the seat base.

3. An improved device for carrying a child comprising a seat base having a pocket formed therein, a rigid plate adapted to be fitted in said pocket to maintain said seat base extended while carrying the weight of a child, sling means consisting of a flap connected to each end of said seat base and a sling of flexible material connected to each flap and adapted to extend diagonally across the body of a wearer from over one shoulder to the opposite side of the body, and a back supporting member connected at each end to one of said flaps and spaced from said seat base, one of said flaps being twisted between said seat base and back supporting member to provide a direct supporting line from the outermost edge of the sling contacting the shoulder of the wearer to the remote edge of the seat base.

4. An improved device for carrying a child comprising, a seat base having a pocket formed therein, a rigid plate adapted to be fitted in said pocket to maintain said seat base extended while carrying the weight of a child, said plate being shaped at one corner substantially complementary to the body portion of a wearer against which it bears, sling means consisting of a flap connected to each end of said seat base and a sling of flexible material connected to each flap and adapted to extend diagonally across the body of a wearer from over one shoulder to the opposite side of the body, and a back supporting member connected at each end to one of said flaps and spaced from said seat base, the flap which is at the end of said seat base accommodating the shaped corner of said plate being twisted between said seat base and back supporting member to provide a direct supporting line from the outermost edge of the sling contacting the shoulder of the wearer to the remote edge of the seat base.

5. A device for carrying a child, comprising: a seat base having a bearing end and an extended end; a wall panel foldably attached to the extended end of said seat base; a shoulder strap secured by its ends to said wall panel and to said bearing end of the seat base, said shoulder strap having a half twist adjacent said bearing end, whereby said seat base may rest by its bearing end against the hip of the wearer with said wall panel located forwardly therefrom, and said strap may follow the body contour around the hip, then diagonally upwardly over the opposite shoulder and then diagonally downwardly and forwardly to said wall panel; and a back strap extending between said wall panel and said shoulder strap and being connected with said strap at a point above its twisted portion.

6. A device for carrying a child, comprising: a seat base; shoulder sling means for said seat base including one end portion providing an upright end wall at one extremity of said seat base, the other end portion of said sling means having a half twist and being attached to the opposite extremity of said seat base; and a back strap extending from said end wall of said sling means and being connected with said other end portion of said sling means in a region above said twisted portion.

7. A device for carrying a child, comprising: a rigid seat base; a flexible end wall attached to one end thereof; a shoulder strap incorporating said end wall and joined to the opposite end of said seat base, the strap being twisted a half turn at said opposite end; and a back strap extending from said end wall and joined to said shoulder strap above its twisted end.

8. A device for carrying a child, comprising: a rigid seat base having a rearward end adapted to be positioned adjacent a hip of the wearer and a forward extended end; flap members attached to the rearward end and extended end of said seat base, the rearward flap being twisted a half turn; a back member connecting said flaps and holding said rearward flap in its twisted position; and a shoulder strap disposed between said flaps adapted to extend diagonally across the wearer over the shoulder opposite from said hip.
